UNITED STATES PATENT OFFICE.

PONTUS OSTENBERG, OF SAN JOSE, CALIFORNIA.

CENTRIFUGAL PUMP.

1,387,660.

Specification of Letters Patent. Patented Aug. 16, 1921.

Application filed January 9, 1920. Serial No. 350,347.

To all whom it may concern:

Be it known that I, PONTUS OSTENBERG, a citizen of the United States, and resident of San Jose, in the county of Santa Clara 5 and State of California, have invented certain new and useful Improvements in Centrifugal Pumps, of which the following is a specification.

My invention relates particularly to the 10 bowl structure of centrifugal pumps.

Centrifugal pump bowls as heretofore formed require the use of cores in casting and are somewhat difficult to properly machine and finish to secure the best results 15 in their practical application.

It is the object of my invention to provide a pump bowl that will be simple in form, that can be cast without the use of a core, in which the several parts are easily accessible 20 for finishing. A further object is to provide a bowl of the character indicated in which the several chambers are easily assembled and connected to the pump casings.

In the drawing:

25 Figure 1 is a vertical cross-section through one-half of an assembled centrifugal pump embodying my invention.

Fig. 2 is a perspective view of one of the bowls shown in section in Fig. 1, part being 30 broken away.

Fig. 3 is a detail sectional view through another embodiment of my invention.

Fig. 4 is a vertical section through one 35 half of a one stage pump embodying my invention.

Referring more particularly to the drawing, 1 indicates a pump shaft mounted in bearing 2 and carrying a plurality of runners 3 as particularly set forth in my Patent 40 No. 1,283,879, dated Nov. 5, 1918, the bearing 2 being a part of the main bearing bowl 4 and connected thereto by webs 5. A portion of a suction casing is indicated at 6 and a portion of a discharge casing at 7 45 the latter being screwed into the top of bearing bowl 4 as shown at 8. The particular type of bowl forming the subject matter of this invention is shown clearly at 9.

Each bowl 9 comprises a cylindrical wall 50 of suitable size threaded upon one inner edge as at 10, its upper edge being carried inwardly toward the axis of the bowl as at 11 to form a discharge opening 12 through which shaft 1 and the pumped water passes. 55 Within the shoulder 13 formed as shown and described are positioned a plurality of

vanes 14, arranged to receive water discharged into bowl 9 and divert it upwardly and inwardly to discharge opening 12, the surface 15 being properly curved for this 60 purpose.

On the outer surface of bowl 9, concentric with opening 12 and somewhat smaller in diameter than bowl 9, is formed an annular boss 16 threaded on its outer surface 65 as at 17 and sloping inwardly toward opening 12 as at 18 and forming a shoulder 19 in which the lower portion of runner 3 operates. On ring or boss 16 are formed a plurality of diffusion vanes 20 so proportioned as to closely approach the lower edges of vanes 14 when placed in position and suitably proportioned and formed to receive water directly from runners 3 and divert the 70 same upwardly to vanes 14.

In assembling this form of my invention it is only necessary to attach as many bowls together as required by engaging the threaded portion 17 of one bowl with the threaded discharge bowl 4, and the threaded portion 75 10 of the same bowl with the threaded portion 17 of the next lower bowl. The successive bowls are positioned by threading into one another as described until the last bowl is reached, whereupon a bottom member 21 80 is screwed into position on said last mentioned bowl. This terminal member 21 is formed with boss 16, threaded portion 17, surface 18, shoulder 19 and vanes 20, but instead of having a bowl portion 9 it is provided with flange 22 projecting downwardly from the inner edge of flange 11 as shown in Fig. 1, and is threaded as at 23 to engage threaded suction casing 6 as at 24.

From the above description it may be seen 90 that each bowl is a simple open casting that may be quickly assembled in any required number according to the number of runners to be used.

In another form of this invention as 100 shown in Fig. 3 the vanes 14 are provided with a ring 25 extending over the upper surface of runner 3 to the hub 3^a thereof, this construction effectually preventing friction of the rising water upon the rotating 105 top portion of runner 3. The object is of course to pass the rising water through opening 12 with a substantially vertical movement and to eliminate as much as practicable the rotary motion imparted thereto 110 by the rotating parts of runner 3.

The runners 3 are preferably made with

a hub 3^a extending upwardly and downwardly from a flange 26 to engage the ends of the hubs of the runners positioned above and below, and the runner blades 27 depend 5 from flange 26 and carry a ring 28 adapted to rotate freely in shoulder 19 and having a central opening of substantially the same diameter as the central opening 12 of the bowl with which it is to be used.

10 In Fig. 4 it is shown that this construction is as readily adapted for use with a single runner as with a plurality of runners.

It is understood that I do not wish to confine myself to the specific forms of the invention set forth in the above specification but to include all variations in form, proportions, construction and methods of assembly and operation that may be included in the appended claims. It should be pointed out that the construction herein set forth provides an exterior pump surface that is devoid of material inequalities thereby facilitating its placing in and removal from a well.

25 I claim:—

1. In a centrifugal pump, a bowl comprising a cylindrical wall section adapted to be attached to upper and lower sections, and have a runner mounted therein, a flange arranged on said wall section adjacent to and within one end thereof and extending within the radius of the runner mounted therein, a diffusion vane arranged on one side of said flange and extending within the radius 30 of the said runner, and a diffusion vane arranged on the opposite side of said flange and extending inwardly to a point adjacent the outer perimeter of the said runner, both of said vanes being formed integrally with 35 said flange.

2. In a centrifugal pump, a bowl comprising a cylindrical wall section adapted to be attached to upper and lower sections, and have a runner mounted therein, a flange arranged on said wall section adjacent to and within one end thereof and extending within the radius of the runner mounted therein, a diffusion vane arranged on the lower side of said flange and extending within the radius 45 of the said runner, and a diffusion vane arranged on the upper side of said flange and extending inwardly to a point adjacent the outer perimeter of the said runner, both of said vanes being formed integrally with 50 said flange.

3. In a centrifugal pump, a bowl comprising a plate having a central opening therein for the discharge of water therethrough, an annular and interiorly threaded flange extending from one side thereof at its outer edge, a diffusion vane arranged in the shoulder between said plate and said flange, and an annular and externally threaded boss of 60 less diameter than said plate extending from the other side thereof.

4. In a centrifugal pump, a bowl comprising a plate having a central opening therein for the discharge of water therethrough, an annular and interiorly threaded flange extending from one side thereof at its outer edge, a diffusion vane arranged in the shoulder between said plate and said flange, an annular and externally threaded boss of less diameter than said plate extending from 70 the other side thereof and a diffusion vane 75 arranged on the outer surface of said boss.

5. In a centrifugal pump, a bowl comprising a plate having a central opening therein for the discharge of water therethrough, an annular and interiorly threaded flange extending from one side thereof at its outer edge, a diffusion vane arranged in the shoulder between said plate and said flange, an annular and externally threaded boss of less diameter than said plate extending from 80 the other side thereof said boss having its outer surface beveled inwardly, and a diffusion vane arranged on said beveled surface.

6. A centrifugal pump including a shaft, a runner mounted thereon including a plurality of depending vanes supporting an annular plate provided with a central opening for the passage of water therethrough, and a bowl having a shoulder formed therein to receive said plate and a discharge opening of substantially the same diameter as the opening in said plate, said bowl having an exteriorly threaded flange to engage the interiorly threaded portion of the member adjacent thereto when assembled, and an interiorly threaded flange to engage the exteriorly threaded portion of the member adjacent thereto when assembled, said bowl having also a diffusion vane arranged thereon to direct water into said discharge opening 90 and a diffusion vane arranged thereon to receive the water passed through said discharge opening and said runner.

7. A centrifugal pump including a shaft, a runner mounted thereon, a bearing for said shaft adjacent said runner, an interiorly threaded bowl formed integrally with said bearing, and a bowl operatively mounted with relation to said runner, said bowl having an exteriorly threaded boss 110 adapted to engage said interiorly threaded first mentioned bowl, an interiorly threaded flange adapted to engage the exteriorly threaded portion of the adjacent member 115 when assembled, an inner discharge opening 120 communicating with the inner portion of said runner, a diffusion vane arranged therein to discharge water through said discharge opening, and a diffusion vane arranged thereon to receive water discharged by said 125 runner.

8. A centrifugal pump including a shaft, a plurality of runners provided with receiving chambers mounted thereon, a shaft bearing adjacent the uppermost runner, a 130

bearing bowl supporting said bearing and spaced a distance therefrom and threaded to engage a threaded discharge casing section and a bowl, and a plurality of bowls 5 of substantially the same exterior diameter as the lower end of said bearing bowl, each bowl having oppositely extending threaded flanges to engage the threaded portions of the bowls adjacent thereto, a central opening 10 alining with said runner chambers, a plurality of diffusion vanes communicating with said opening, and a plurality of

diffusion vanes arranged to receive water from said runners, and a bottom member threaded to engage the adjacent threaded 15 flange of the bottom bowl, said bottom member also being threaded to engage a threaded suction casing section, having a central opening therein communicating with the receiving chamber of the adjacent runner and 20 having a plurality of diffusion vanes arranged thereon to receive water from said runner.

PONTUS OSTENBERG.
